ABSTRACT

A tuning assembly (42) is disclosed for selectively oscillating the frequency of an electromagnetic field within a hermetically sealed pulsed magnetron (12), comprising a rigid, hermetically sealed housing (14), apparatus for generating the electromagnetic field therewithin (32, 34, and 36), and elements for defining a cavity (30) within the housing for establishing the frequency of the electromagnetic field. The tuning assembly (42) includes electrically conductive members (54) mounted for linear movement within the cavity (30) to oscillate the established frequency. Elements (52) disposed within the rigid housing (14) are provided for mounting the electrically conductive members (54), and are adapted for oscillatory movement at a predetermined mechanical resonant frequency to move the electrically conductive members (54) linearly. The tuning assembly (42) incorporates a highly efficient electron-emitter (cathode) assembly (24, 102) arranged in the form of a tightly-wound, helical member (102), the cathode assembly (24, 102) being directly heated and composed of porous tungsten impregnated by a mixture of barium and calcium aluminates. The helical member (102) is machined and has a rectangular cross-section, so as to present a substantially cylindrical emitting surface having a maximum emitting area. Finally, a power source (108) is provided exterior to the rigid housing (14) and is magnetically coupled to the mounting elements (44) for exciting them.

**PULSED MAGNETRON TUBE HAVING
IMPROVED ELECTRON EMITTER ASSEMBLY**

**CROSS REFERENCE TO RELATED
APPLICATIONS**

This application is a continuation-in-part of U.S. patent application Ser. No. 548,203 filed Nov. 2, 1983, abandoned which was a continuation-in-part of U.S. patent application Ser. No. 362,895, filed Apr. 19, 1982, and now abandoned, which was a divisional application of U.S. patent application Ser. No. 066,226, filed Aug. 13, 1979, now U.S. Pat. No. 4,331,935 dated May 25, 1982.

TECHNICAL FIELD

This invention relates generally to radio frequency power devices and more particularly to pulsed magnetron tubes having tuning assemblies for oscillating the frequency output of such devices. More specifically, the subject invention relates to a novel tuning assembly for oscillating the frequency of an electromagnetic field generated within a hermetically sealed magnetron tube, to thereby oscillate the frequency output of such device. The subject invention also relates to a novel electron emitter assembly, which provides the greater efficiency needed in a high peak-power pulsed magnetron used for radar applications.

BACKGROUND OF THE INVENTION

Radio frequency power devices are well known in the art. Such power devices may generate radio frequency outputs at a fixed frequency or at variable frequencies oscillating within a specified operating frequency band. In general, such radio frequency power devices include therewithin a hermetically sealed housing which is either evacuated, as in the case of a vacuum tube or a magnetron, or is filled with an inert gas. A variety of well known systems are utilized to generate an electromagnetic field within the hermetic housing with the current induced from such an electromagnetic field being directed to an output antenna.

One commonly used arrangement for generating such an electromagnetic field includes positioning an anode ring about a centrally disposed cathode within the hermetic housing, and then establishing a magnetic field around the anode. This is commonly done by positioning a pair of magnets on either side of the anode. In this manner, an electrical field is created between the cathode and anode, and a magnetic field is generated within the interaction space between the cathode and anode, thereby establishing an electromagnetic field at the anode. In this particular arrangement, the anode ring defines a cavity space radially inwardly thereof wherein the frequency of the electromagnetic field is established. In other arrangements, such as in a coaxial magnetron tube, the cavity space wherein the frequency of the electromagnetic field is defined may be located exterior to the anode.

In the above described arrangement, the frequency of the electromagnetic field is defined by the physical size and shape of the cavity as well as the conductive properties of the material utilized to form the cavity. One known cavity arrangement includes a plurality of tabs or vanes projecting radially inwardly from the inner surface of the anode ring, and the frequency of the electromagnetic field is determined by the conductive properties of the vanes, the size of the vanes, the spacing

between the vanes, and the manner in which the vanes may be electrically interconnected at their radially inner edges. Thus, by adjusting these variables of the vane structure and thereby changing the overall volume of the cavity, any desired frequency may be pre-selected prior to construction of the radio frequency device. The manner in which the vane structure is constructed and altered so as to establish a desired fixed frequency is well known in the art and will not be discussed in any detail herein.

Once the shape and the volume of the frequency determining cavity is established, the frequency of the electromagnetic field generated within such a device is set, and the resultant frequency output of the device becomes fixed. In variable frequency power devices, however, the frequency of the electromagnetic field within the hermetic housing is tunable or varied in an oscillating manner by changing the volume of the frequency determining cavity in an oscillatory fashion, thereby changing the inductive properties thereof. One known technique for changing the volume of the frequency determining cavity includes positioning an electrically conductive member within the cavity and oscillating that member therewithin, thereby varying the volume of the cavity in an oscillatory manner. To achieve such oscillatory motion of an electrically conductive member within the cavity, prior devices have commonly utilized mechanical arrangements for moving the electrically conductive member.

One such mechanical tuning arrangement utilizes a thin wall bellows or diaphragm as part of the hermetic housing. The electrically conductive members are then mechanically connected to such a bellows or diaphragm, and the bellows or diaphragm are mechanically oscillated by a motor located outside the hermetic housing.

Another known tuning arrangement for changing the volume of the frequency determining cavity includes positioning electrically conductive members within the cavity and rotating such members along the inner surface of the anode ring. Such rotation is effected by magnetically coupling the rotating electrically conductive member to an electromagnetic power source disposed outside the housing. A distinct disadvantage to this latter technique, however, is that by rotating an electrically conductive member within the frequency determining cavity, the electromagnetic field frequency can be varied, but not in an oscillatory manner.

The movable bellows or diaphragm arrangement described above, however, also has certain disadvantages. One major disadvantage with this mechanical tuning arrangement is that the walls of the bellows or diaphragm must be relatively thin to effect such movement and are thereby subject to mechanical fatigue and failure. If such a bellows or diaphragm does fail, the vacuum or inert gas environment within the hermetic housing is destroyed, and the power source thereby becomes useless. Another disadvantage is that since the bellows or diaphragm must be constructed from a thin walled material, atmospheric gas can penetrate such thin material over a period of time and can thereby affect the internal environment. Therefore, such mechanical arrangements have a relatively short storage or shelf life.

A further disadvantage of the above mechanical tuning assemblies is that a significant energy input is required to operate such assemblies. This requirement is

due to the mechanical resistance offered by the bellows or diaphragm arrangement as well as to the atmospheric dampening effect on the mechanical parts located exterior to the hermetic housing or envelope.

The novel tuning assembly of the present invention, however, overcomes the disadvantages of known mechanical tuning assemblies, and provides a relatively simple yet efficient means for oscillating the frequency of the electromagnetic field generated within such radio frequency power sources.

U.S. Pat. No. 4,223,246 to Osepchuk discloses an entirely different type of magnetron than is being disclosed and claimed in the present case. Osepchuk discloses a relatively low-powered magnetron device, apparently used for a microwave oven or other microwave heating applications. This device provides continuous waves of the order of 500 to 2000 watts. The present invention, by contrast to Osepchuk, is a high peak-power, pulsed magnetron for radar applications. The present device provides power outputs several orders of magnitude higher, namely, in the power range of 20,000 watts to more than a megawatt. Osepchuk's cathode is made of thoriated tungsten wire with a round cross section capable of output current in the milliampere range. The present invention, by contrast, has a highly efficient helical cathode which is machined (not made of wire), has a rectangular cross section, and is capable of output current of the order of amperes, not milliamperes. The helix of the present invention is tightly wound and presents an overall cylindrical configuration with a much larger emission surface. The emissivity of the cathode in the present invention is also greatly enhanced by the material of which it is made, namely, 82% dense porous tungsten impregnated with a mixture of barium and calcium aluminates.

U.S. Pat. No. 2,700,000 to Levi et al discloses a thermionic cathode which is indirectly heated by heater 3 or 7. This patent shows a cathode impregnated with an alkaline earth composition but does not show or suggest a directly heated cathode for use in a pulsed magnetron having considerably higher current and power outputs.

Neither of the above-mentioned patents to Osepchuk or Levi et al show or suggest the type of highly efficient cathode needed for a high peak-power pulsed magnetron tube, such as is disclosed and claimed in the present application. For one thing, neither patent contemplates the current and power outputs required in the present invention, namely of the order of amperes and megawatts, and therefore neither patent contemplates a need for the emission efficiency of the cathode disclosed and claimed in this application. Neither patent shows or suggests a directly heated cathode made highly efficient by being impregnated with a very effective mixture of barium and calcium aluminates. Moreover, it should be understood that a pulsed magnetron has to oscillate at the beginning of a pulse. The particular combination of improved emissivity and more rapid warm up in this cathode allows a pulsed magnetron to start oscillating much faster than is true of any other pulsed magnetron known to the applicant.

SUMMARY OF THE INVENTION

Therefore, it is one object of the present invention to provide a tuning assembly for selectively oscillating the frequency output of a radio frequency power source.

It is another object of the present invention to provide a tuning assembly for selectively oscillating the frequency of an electromagnetic field within a hermeti-

cally sealed device wherein the device has a rigid or hermetic housing.

A further object of the present invention is to provide a magnetron tube having an oscillating frequency output and a rigid, hermetically sealed housing.

It is yet another object of the present invention to provide a tunable magnetron tube wherein the mechanical components of the tuner assembly are located entirely within a rigid, inflexible hermetic housing.

10 It is a still further object of the present invention to provide a high peak power, pulsed magnetron tube for radar applications, said tube having a directly heated, helical cathode member constructed from porous tungsten impregnated with an emissive material.

15 It is still another object of the present invention to provide a greatly improved electron emitter assembly for a high peak-power, pulsed magnetron which is directly heated and has greater efficiency because of its improved shape, high electron emissivity and rapid warm-up.

20 In accordance with the invention, a tuning assembly is provided for selectively oscillating the frequency of an electromagnetic field within a hermetically sealed device wherein such device includes a rigid, hermetically sealed housing, a mechanism for generating an electromagnetic field within the housing, and elements for defining a cavity within the housing for establishing the frequency of the electromagnetic field. The novel tuning assembly includes electrically conductive members mounted for linear movement within the frequency defining cavity to selectively vary the volume of the cavity to oscillate the established frequency of the electromagnetic field. A mounting assembly for mounting the electrically conductive members is disposed within 25 the rigid housing and is adapted for oscillatory movement at a pre-determined mechanical resonant frequency to move the electrically conductive members in the aforementioned linear manner. Finally, a power source is located exterior to the rigid housing and is magnetically coupled to the mounting assembly for 30 magnetically coupling the mounting assembly to the electrically conductive members.

35 The tuning assembly of the present invention may be adapted to oscillate the electromagnetic field frequency within any hermetically sealed device having a rigid, hermetically sealed housing and a frequency defining cavity within such housing. The subject invention, however, is particularly useful in radio frequency power sources such as variable frequency magnetron tubes.

40 In one preferred embodiment of the present invention, the mounting mechanism includes a support member for securely mounting the electrically conductive members within the housing. A spring mechanism is provided for interconnecting the support member and the housing and is adapted to permit oscillatory movement of the support member within the housing. The pre-selected mechanical resonant frequency of the mounting mechanism is directly determinable in accordance with known techniques from the mass of the 45 electrically conductive member and the mounting mechanism as well as the spring rate of the spring mechanism. The support member is maintained at a constant pre-determined oscillatory movement by pulsing the power source at the same frequency as the preselected mechanical resonant frequency of the mounting mechanism. In this manner, the frequency of the electromagnetic field, and thereby the output frequency of the device, may be selectively oscillated in accordance with 50 55 60 65

the pre-selected mechanical resonant frequency of the tuning assembly.

The improved high peak power, pulsed magnetron disclosed in the present application has a highly efficient electron emitter (cathode) assembly having a machined, tightly-wound, helical cathode member having a rectangular cross section. The cathode member provides a substantially cylindrical outside configuration having a much larger emission surface than is found in the prior art devices. The emissivity of the cathode is greatly enhanced by the material of which it is made, preferably 82% dense porous tungsten impregnated with a mixture of barium and calcium aluminates. The combination of the directly heated cathode member with all the above-mentioned features in combination provides a greatly improved electron emitter assembly having the rapid warm-up and high power capacity which is necessary for pulsed magnetrons for radar applications.

BRIEF DESCRIPTION OF THE DRAWINGS

The novel features which are believed to be characteristic of the present invention are set forth in the appended claims. The invention itself, however, together with further objects and attendant advantages thereof will become apparent and best understood by reference to the following detailed description taken in connection with the accompanying drawings, setting forth by way of illustration and example certain embodiments of the invention in the several figures of which like reference numerals identify like elements, and in which:

FIG. 1 is a side-sectional view of a magnetron tube mounted within a device, illustrating one embodiment of the tuning assembly of the present invention;

FIG. 2 is a cross-sectional view taken substantially along the line 2—2 of FIG. 1, illustrating the frequency defining cavity of the magnetron tube of FIG. 1;

FIG. 3 is a cross-sectional view taken substantially along the line 3—3 of FIG. 1, illustrating the mounting mechanism of the present invention;

FIG. 4 is an exploded side elevation view, with some parts in section, of the tuning assembly of the present invention in relation to the anode structure of the magnetron tube shown in FIG. 1;

FIG. 5 is an enlarged front perspective view of the electrically conductive members and support member of one embodiment of the tuning assembly of the present invention;

FIG. 6 is a side elevation view of the embodiment illustrated in FIG. 5;

FIG. 7 is an enlarged front perspective view of the mounting members and support member of a second embodiment of the tuning assembly constructed in accordance with the present invention;

FIG. 8 is a side elevation view of the embodiment illustrated in FIG. 7;

FIG. 9 is a side elevation view of one electrically conductive member of the embodiment illustrated in FIGS. 5 and 6;

FIG. 10 is a side elevation view of one electrically conductive member of the embodiment illustrated in FIGS. 7 and 8.

FIG. 11 is a side elevation showing a greatly enlarged view of the electron emitter assembly of the present invention; and

FIG. 12 is a sectional view of the electron emitter assembly as shown in FIG. 11, taken along section line 12—12 in FIG. 11.

DETAILED DESCRIPTION OF THE PREFERRED EMBODIMENTS

Referring to FIG. 1, a hermetically sealed device such as a magnetron tube 10 is illustrated and incorporates the tuning assembly of the present invention. Radio frequency power sources such as the magnetron tube 10 have many different uses, FIG. 1 illustrating the tube 10 mounted in an enclosure 12. It is to be understood, however, that the present invention is not to be limited for use in such a magnetron tube 10, but rather may be utilized in any device wherein the device includes a rigid hermetic housing and requires selective oscillation of an electromagnetic field generated within the housing.

The illustrated magnetron tube 10 includes a hermetically sealed housing 14 having an evacuated internal atmosphere. The housing 14 is entirely rigid and is comprised of a tuner assembly housing 16, an anode assembly 18, and two magnetic pole piece housings 20 and 22 disposed on either side of the anode 18. These members 16-22 are all heliarc welded together to form the hermetically sealed housing 14.

Disposed within the housing 14 is the anode assembly 18, which forms a part of the housing 14, and a cathode assembly 24 spaced from the anode 18. In preferred form, the cathode 24 is centrally disposed along the longitudinal axis of the housing 14, which in preferred form is annular in shape. The anode 18 preferably is in the form of an annular ring 26 having an inner raised rim portion 28 projecting radially inwardly toward the cathode 24 from the center portion of the ring 26. The inner surface of the ring 26 defines generally a cavity area 30 (FIG. 2) which is disposed between the anode 18 and the cathode 24. The cavity area 30 comprises the area to establish the frequency of the electromagnetic field generated at the anode 18 by the electrons emitted from the cathode 24, which interact with the anode 18 and the magnetic field within the anode 18, as described in greater detail below.

Disposed on either side of an coaxially with the anode ring 26 are a pair of magnetic pole pieces 32 and 34. The magnetic pole pieces 32 and 34 act in conjunction with a permanent magnet assembly 36 so as to create a magnetic field about the anode 18 and the cathode 24. The interaction of the electrical field between the cathode 24 and the anode 18 and the magnetic field created by the magnetic assembly 36 and the pole pieces 32 and 34 occurs within the cavity 30 to establish an electromagnetic field at the anode 18.

The electromagnetic field at the anode 18 creates an alternating current in the anode 18 which passes along an antenna member 38. The alternating current induced in the anode 18 flows back and forth along the antenna 38 and changes at a specific radio frequency rate established by the cavity 30. This current generates electromagnetic waves from the antenna 38 which propagate outwardly through the radome structure 40.

Referring more particularly to FIGS. 1, 3, and 4, the magnetron tube 10 includes a tuning assembly 42 constructed in accordance with the present invention.

The assembly 42 includes the outer hermetically sealed housing 16, which is preferably annular in shape, and a tuning mechanism 42. More particularly, a mounting assembly 44 is disposed coaxially within the housing 16. In preferred form, the mounting assembly 44 includes a tubular support member 46 suspended for linear reciprocating or oscillatory movement within the

housing 16, and a tubular support element 48 which has a smaller diameter than the diameter of the support member 46 and is mounted on an annular flange 50 coaxially with and for linear movement with the support member 46.

An electrically conductive element 52 is mounted on the end of the tubular support element 48 and extends into the cavity 30 defined by the anode 18. In preferred form, the electrically conductive element 52 includes a plurality of electrically conductive members 54 circumferentially spaced about the end of the support element 48 and projecting into the cavity 30 as described in greater detail below. The electrically conductive element 52, the support element 48 and the support member 46 are all secured together to form the tuning mechanism 43 and move in unison in a linear oscillating manner.

A spring assembly 56 is provided for interconnecting the mounting assembly 44 to the housing 16. In preferred form, the spring assembly 56 includes a plurality of leaf springs 58 securely mounted at one end to the support member 46 adjacent to the junction of the support element 48 and at the other end to the housing 16, and a plurality of leaf springs 60 securely mounted to the lower opposite end of the support member 46 and the housing 16. The ends of each spring 58, 60 are securely mounted so that the mounting assembly 44 is suspended within the housing 16. In the illustrated form, there are four leaf springs 58 and four leaf springs 60, each in the form of an elongated "s". The springs 58 are positioned equidistantly about the circumference of the support member 46, and the springs 60 are also disposed equidistantly about the circumference of the support member 46.

In the preferred form, the support member 46 and the support element 48 are constructed from non-magnetic material. To assist in exciting the oscillatory movement of the mounting assembly 44, the mounting assembly 44 further includes an annular magnetic member 62 secured about the support member 46 by a pair of annular brackets 64, 66. The magnetic member 62 is adapted to move in uniform linear movement with the mounting assembly 44.

The tuning mechanism 43, which includes the entire mounting assembly 44 and the electrically conductive element 52, is designed to move at a natural, preselected mechanical resonant frequency in a linear direction coaxial with the longitudinal axis thereof. The natural resonant frequency of the tuning mechanism 43 is dependent on the mass and spring rate of the mechanism 43. Therefore, the natural resonant frequency of the tuning mechanism 43 may be readily pre-selected by varying either the mass of the mechanism 43 and/or the spring rate of the spring assembly 56. The techniques for calculating the natural resonant frequency from the mass and spring rate are well known in the art and will therefore not be described herein. Once the mass of the tuning mechanism 43 and the spring rate of the spring mechanism 56 have been selected, however, the natural resonant frequency of the mechanism 43 may still be altered by inserting a spring coil 66 (FIG. 1) within the support member 46. The spring coil 66 is affixed to the inner surface of the flange 50 and the inner surface of the bottom portion of the housing 16. The spring rate of the coil spring 66 may be selectively varied so as to achieve the desired natural resonant frequency for the tuning mechanism 43.

To excite the tuner mechanism 43 at its natural resonant frequency, a power source 68 is provided about the exterior surface of the housing 16 and is magnetically coupled to the magnetic member 62. In preferred form, the power source 68 comprises an electromagnetic coil 70 wrapped around the housing 16. The coil 70 is adapted to be alternately energized and de-energized in a pulsating manner so that when the coil 70 is energized, the magnetic member 62 is attracted to move the tuning mechanism 43 in a first linear direction. After such a pulsing of the coil, the coil 70 returns to a deenergized state, and the spring mechanism 56 returns the tuning mechanism 43 beyond its initial position, thereby moving the mechanism 43 in a second opposite linear direction. Therefore, the coil 70 is repeatedly pulsed at the same frequency rate as the natural resonant frequency of the tuning mechanism 43 so as to maintain the tuning mechanism 43 in a constant oscillating motion. This oscillating movement of the tuning mechanism 43 causes the electrically conductive element 52 to oscillate within the cavity 30. This mechanical oscillation of the electrically conductive element 52 within the cavity 30 changes the volume of the cavity 30 in an oscillatory manner, and as the volume of the cavity 30 is changed, the inductance of current from the electromagnetic field is changed in a similar oscillatory manner so as to vary the frequency of the electromagnetic field within the cavity 30 in such an oscillatory manner.

Referring to FIGS. 1, 2, and 4, the annular assembly 18 includes the anode ring 26 and the rim member 28. In the preferred embodiment, the annular anode assembly 18 further includes a plurality of spaced tabs in the form of vanes 72 integrally formed with the rim 28 and extending radially inwardly toward the cathode 24. Each vane 72 is a flat electrically conductive member having a plane aligned with the central axis of the anode ring 26. The vanes 72 divide the cavity 30 into a plurality of individual cavities or chambers 74 defined between the vanes 72. In addition, a plurality of electrically conductive strap members 76 are preferably provided in the form of annular rings which selectively interconnect a plurality of vanes 72. In preferred form, there are two strap members 76 and 76' which interconnect alternate vanes 72 so that one-half of the vanes 72 are electrically connected to one strap, and the other half of the vanes 72 are interconnected to the second strap 76'. The straps are utilized in conjunction with the vanes 72 and the ring 28 to define a particular frequency for the electromagnetic field created within the cavity area 30. Use of such straps 76, 76', and the technique for calculating the appropriate dimensions and arrangements of the vanes 72, the straps 76, 76', and the ring 26, to establish a specific frequency, are well known in the art and are therefore not disclosed specifically herein.

When the anode assembly 18 is constructed in the above described preferred form, the electrically conductive element 52 is preferably in the form of a plurality of electrically conductive members 54. The members 54 are mounted circumferentially about the end of the support element 48 and are appropriately spaced so that each member 54 is adapted for positioning within one cavity 74. The end portion of each member 54 is positioned so that it remains within a cavity 74 as the tuning mechanism 43 is oscillated. As the tuning mechanism 43 oscillates the electrically conductive member 54 also oscillates within a cavity 74, thereby changing the volume of each cavity 74 in a uniform oscillating manner. Thus, the entire volume of the cavity area 30 is

changed in a uniform oscillating manner. This change in the volume of each cavity 74 by the presence of an electrically conductive member therein alters the inductance of current by the annular ring 28 and changes the frequency of the electromagnetic field present within the cavity area 30. This change in the electromagnetic field is proportional to the change of the volume of the cavity area 30, so that the frequency of the electromagnetic field oscillates in a proportional manner with the oscillation of the tuning mechanism 43. As the frequency of the electromagnetic field within the cavity area 30 oscillates, the output frequency of the magnetron tube 10 similarly oscillates about the pre-selected frequency.

Referring to FIGS. 1 and 4, the magnetic pole pieces 32 and 34 are preferably comprised of a soft magnetic material, such as iron, which is not permanently magnetized. The magnetic pole pieces 32 and 34 direct the magnetic field from the permanent magnetic assembly 36 into the interaction space between the cathode assembly 24 and the anode assembly 18. The permanent magnetic assembly 36 may comprise any known arrangement. In the illustrated embodiment, the assembly 36 includes two permanent magnets 78 and 80 interconnected by steel tubes 82, 82', and a sleeve member 84. Thus, the strength of the magnetic field may be selectively varied depending upon the strength of the permanent magnets 78, 80.

The magnetic pole piece 34 includes an annular bracket assembly 86, which functions to mount the permanent magnet 80 as well as to form the housing 20, and a magnetic pole piece member 88. The magnetic pole piece member 88 includes a plurality of orifices or channels 90 which are coaxially aligned with the longitudinal axis of the electrically conductive members 54 and the anode ring 26. The channels 90 function as passageways for the electrically conductive members 54 between the support element 48 and the cavities 74.

Referring more specifically to FIGS. 4, 5, 6, and 9, one preferred embodiment of the electrically conductive members 54 is illustrated therein. In this embodiment, each electrically conductive member 54 comprises a pin member 92 constructed from any suitable electrically conductive material. The pin 92 has a substantially uniform diameter along its length, and includes a base portion 94 which is notched to form a ledge for mounting the pin 92 to the support element 48. The diameter of the pin 92 is selected so that the pin 92 freely passes through a channel 90 and is positioned between a pair of vanes 72 without making contact therewith.

When the electrically conductive member 54 is in the form of the pin 92, however, there is a tendency for secondary resonant effects to be introduced into the magnetic pole piece 34 due to the oscillation of the electrically conductive pin 92 within the channel 90. When it is desired to avoid such secondary resonant effects, a second preferred embodiment of the invention may be utilized.

Referring to FIGS. 7, 8 and 10, wherein the second embodiment of the electrically conductive member 54 is illustrated, the member 54 is in the form of an elongated member 95 having an expanded diameter end portion 96 for positioning within a cavity 74. The end portion 96 is constructed from electrically conductive material and is of sufficient diameter to substantially fill the cavity 74 in cross-sectional dimension, as illustrated in FIG. 2. The elongated member 95 also includes a shaft portion 98

which interconnects the end portion 96 to the support element 48, and the diameter of the shaft portion 98 is substantially less than the diameter of the end portion 96. The shaft portion 98 is sized so that the shaft portion 98 remains within the channel 90 as the tuning mechanism 43 oscillates. In this manner, the amount of material within the channel 90 is substantially reduced, which in turn substantially reduces the secondary resonant effects. Furthermore, the shaft portion 98 may also be constructed from an electrically non-conductive material such as a ceramic material. In this manner, the secondary resonant effects in the magnetic pole piece 34 are almost nonexistent. The shaft 98 preferably includes a base portion 100 which is notched to form a ledge for attachment to the support element 48.

Referring now to FIG. 1 again, the cathode structure 24 is preferably in the form of a helical, spring-like member 102 positioned between two end plates 104, 106. The helical member 102 is preferably constructed from 82% dense porous tungsten impregnated by electron emissive material, preferably a mixture of barium and calcium aluminates. The helical member 102 is machined and has a rectangular cross-section, so as to present a substantially cylindrical emitting surface having a maximum emitting surface area. This particular cathode structure is directly heated by a current from conductors 108. This direct heating of the impregnated tungsten causes improved electron emission by the cathode 24 and rapid warm-up. It has been found that this arrangement for heating the cathode 24 permits warm-up in about 3 to 5 seconds instead of about 12 to 20 seconds if the cathode 24 were indirectly heated in the conventional way. This combination of two cooperating features: (1) the substantially cylindrical emissive surface providing greatly increased surface area, and (2) the directly heated cathode with fast warm-up, together provide a much more efficient electron emitter assembly than has been previously known in a pulsed magnetron. Such efficiency is important and is much needed in a high peak-power pulsed magnetron for radar applications, such as the present invention. By contrast, such efficiency has not been known before and was not needed in relatively lower-powered magnetrons providing continuous waves of the order of 500 to 2000 watts, such as in the Osepchuk patent mentioned earlier.

Look now at the greatly enlarged views of the electron emitter assembly 24, as shown in the side elevational view of FIG. 11 and the sectional view of FIG. 12. In these views, it may be seen clearly that the cathode helical member 102 is tightly-wound and has a rectangular cross section. Thus, helical member 102 presents an outside profile which is substantially cylindrical. First, this geometry gives it a larger emitting surface area than has been previously known in a cathode for a magnetron. Secondly, the cathode (24, 102) is directly heated by power source 108 so as to also provide fast warm-up. Thirdly, emission efficiency of the cathode is maximized by making the cathode of 82% dense porous tungsten impregnated with a mixture of barium and calcium aluminates. The combination of the above-mentioned three features, all cooperating together, makes this electron emitter assembly more efficient than any known in a prior art pulsed magnetron and makes it possible for this magnetron to come up to a peak power of up to a megawatt or more very fast. It should be mentioned that a pulsed magnetron has to oscillate at the beginning of a pulse and therefore has an

inherent requirement to come up to power much faster than continuous wave magnetrons.

The tuning assembly 42 as described above provides a constantly variable frequency across a specific frequency band, generally varying 5% on either side of a center frequency. For example, the tuning mechanism 42 as disclosed in the magnetron 10 of FIG. 1 can provide a 100-300 MHz frequency variation around any selected center frequency, the selected center frequency being established by the dimensions of the anode assembly and the cavity defining elements. Such a center frequency can be established at any desired frequency, for example, between 1-50 gigahertz, by utilizing known technique in the art. To achieve such a frequency variation, the natural resonant frequency of the tuning mechanism 43 may be generally set at approximately 15-20 cycles per second. However, as previously described, the natural resonant frequency of the tuning mechanism 43 may be established at any selected level, thereby permitting any desired frequency variation occur in the electromagnetic field at the anode 18.

As can be seen from the above, the present invention provides a novel mechanism whereby the frequency of an electromagnetic field within a hermetically sealed device may be readily varied in an oscillatory manner. This oscillatory variation of the frequency is achieved by a mechanical oscillating device which has all moving mechanical components disposed within a rigid housing. Therefore, there are no thin walled or flexible portions required in the hermetically sealed housing, which design prevents atmospheric leakage and provides a long storage or shelf life. Furthermore, in the example wherein the tuning assembly of the invention is used in a magnetron or other vacuum tube, all the mechanical parts perform within a vacuum, thereby obviating the dampening effect of any atmospheric environment. Finally, the tuning assembly of the present invention is based on a natural resonant frequency of the tuning mechanism. To oscillate this mechanism in a desired manner, only a small amount of energy in a pulsed form is required, in as much as the power source for moving the tuning assembly is magnetically coupled to the tuning mechanism.

From the above, it should be apparent that applicant has incorporated into his pulsed magnetron tube a cathode structure which is much more efficient than anything disclosed by any of the prior art patents or any combination thereof. The cathode assembly disclosed and claimed herein is a machined, tightly-wound, helical spring-shaped structure having a rectangular cross-section which presents much more emitting surface than is present in any of the known prior art devices. The present invention presents substantially a cylindrical surface with much greater emitting area than is presented by a helical cathode made of round wire. Moreover, it should be understood that a pulsed magnetron has to oscillate at the beginning of a pulse. The particular combination of improved emissivity and more rapid

warm-up in this cathode allows a pulsed magnetron to start oscillating much faster and to come up to full power much faster than is true of any other pulsed magnetron known to the applicant.

It will be understood that the invention may be embodied in other specific forms without departing from the spirit or central characteristics thereof. The present examples and embodiments, therefore, are to be considered in all respects as illustrative and not restrictive, and the invention is not to be limited to the details given herein but may be modified within the scope of the appended claims.

What is claimed is:

1. A pulsed magnetron tube comprising:
rigid hermetic housing means;

a cathode assembly disposed along the center axis of said housing means; said cathode assembly comprising a directly heated, tightly wound, machined, helical element having a rectangular cross section, said helical element being constructed from 82% dense porous tungsten impregnated with an emissive material comprising a mixture of barium and calcium aluminates;

an anode assembly disposed within said housing means;

means for generating an electromagnetic field at said anode assembly;

means disposed within said housing means for defining the frequency of said electromagnetic field; tuning means mounted within said housing means for linear movement to selectively vary said frequency in an oscillatory manner; said tuning means being concentric with said cathode assembly and mounted at the same end of said magnetron tube as said cathode assembly; and

power means disposed exterior to said housing means for exciting said tuning means;

whereby said cathode assembly presents a substantially cylindrical emitting surface having a maximum emitting area and maximum emitting efficiency.

2. In an electron emitter assembly for a pulsed magnetron, the improvement comprising a cathode structure comprising a directly heated, tightly wound, machined, helical element having a rectangular cross section, said cathode structure being composed of 82% dense porous tungsten impregnated with an electron-emissive material comprising a mixture of barium and calcium aluminates;

whereby said cathode combines the features of efficient shape in the form of a substantially cylindrical emitting surface having a maximum emitting area, maximum electron emissivity provided by highly emissive materials and rapid warm-up, thereby providing an electron emitter assembly capable of functioning efficiently in a high-power, pulsed magnetron tube.
